UNITED STATES PATENT OFFICE.

JOHN NELSON, OF GLASGOW, SCOTLAND.

APPARATUS FOR THE CRACKING OF HYDROCARBON OILS AND THE LIKE.

1,412,540.

Specification of Letters Patent. Patented Apr. 11, 1922.

Application filed March 2, 1918. Serial No. 219,950.

To all whom it may concern:

Be it known that I, JOHN NELSON, a subject of the King of England, residing in Glasgow, Scotland, have invented certain new and useful Improvements in Apparatus for the Cracking of Hydrocarbon Oils and the like, of which the following is a specification.

The present invention relates to apparatus for "cracking" hydrocarbon oils and the like.

In processes heretofore employed for this purpose it has been customary to pass the hydrocarbon through retorts, tubular chambers or the like partly filled with solid contact-materials such as iron, nickel, or earthenware and heated to an appropriate temperature. In operating with solid contact-substances, however, it has been found that difficulties and irregularities of working are apt to occur, chiefly on account of the gradual accumulation of carbonaceous deposits in the interstices of the contact-material or at constricted parts of the chamber. A further disadvantage has been that, as a rule, it has not been easy to maintain a uniform temperature in the contact-material itself and the consumption of fuel for heating has been somewhat wasteful.

The object of the present invention is to obviate these difficulties and to improve the cracking process generally.

The present invention consists in an improved apparatus for cracking oil by a process in which there is used as contact-substance a suitable liquid material, such as molten metal, instead of the solid bodies hitherto employed, the liquid being agitated, as for example by passage of the hydrocarbon vapours and gases through it.

The selection of the liquid substance to be used depends, among other considerations, upon the working temperature required. In operating at moderate temperatures (such as are employed in the production of volatile spirits for use in petrol engines) I prefer to use a bath of molten lead as the contact-substance, and to pass the hydrocarbon or its vapours into the bath at a suitable distance below its surface. The gases and vapours rushing up through the liquid metal keep it vigorously agitated: local accumula-

tions of carbonaceous matter are prevented and the maintenance of a uniform temperature in the contact-substance is facilitated. 55

It will be understood that the liquid contact-substance comes directly into contact with the hydrocarbon itself and is not used merely as a means for the external heating of the contact-chamber. The cracking takes 60 place solely in contact with the molten metal, or substantially so.

If the hydrocarbon to be cracked contains tarry matters or the like which cannot be wholly vapourized during the cracking 65 process, it may be distilled from an auxiliary vessel and the distillate or vapours be then subjected to the cracking process.

The extent of the cracking may be varied by varying the depth at which the hydrocarbon or its vapours are delivered beneath the surface of the liquid contact-substance.

As the time during which the hydrocarbon and its product remain in contact with the hot liquid substance is very brief, the 75 whole product or any desired fraction thereof may be subjected to one or more re-treatments; for example the heavier fraction, condensed out of the hot vapours by means of a dephlegmator in the known 80 manner, may be thus retreated.

Figure 1 is a vertical section of a modification.

Figure 2 is a detail vertical section.

Figure 3 is a plan view partly broken 85 away showing the apparatus of Figure 1.

Figure 4 is a vertical section of a modification.

Figure 5 is a plan view of the apparatus shown in Figure 4. 90

Figure 6 is a vertical section through another modification, and

Figure 7 is a detail vertical view of the apparatus shown in Figure 6 taken at right angle thereto. 95

If temperatures exceeding those at which lead is satisfactorily employed are to be adopted, metals or alloys of higher melting-point than lead may be used as contact-substance and the apparatus may be constructed 100 of fireclay or other refractory material.

According to this invention one form of apparatus consists of a covered horizontal tank set in a furnace and containing the

liquid contact-substance. The tank is provided with oil inlet and vapour-outlet pipes and with a series of internal vertical partitions so arranged that the hydrocarbon vapours are caused to flow alternately up over or down under the partitions and thus to bubble up through the contact-substance in the alternate compartments. To ensure a steady flow of the vapours, the lower edges 10 of the alternate partitions may be serrated or provided with perforations for breaking up the vapours into small streams.

A preferred apparatus of this type is shown diagrammatically in sectional elevation, cross-section, and plan respectively in Figures 1, 2 and 3 of the accompanying drawings. The covered horizontal tank F which is of V-shaped cross-section and into which the oil is fed under pressure through the inlet pipes K, contains the liquid contact-substance for example molten lead E and is provided with vapour-outlet pipes L. The tank is divided into a series of compartments (of which four are shown in the drawing) by 15 transverse partitions G having ports G¹ at the upper part for the passage of the hydrocarbon vapours, and these compartments are further divided by a series of depending partitions H, the lower parts of which are 20 curved and immersed to a suitable depth in the molten lead or other liquid contact substance as shown. The hydro-carbon vapours are by this arrangement caused to pass through the apparatus in the direction shown 25 by the arrows and are subjected repeatedly to the action of the molten lead. The V-shaped cross-section of the tank is specially 30 advantageous when two or more such units are mounted side by side in one furnace.

Figures 4 and 5 show, in sectional elevation and plan respectively, a modified arrangement in which the horizontal tank C, which is preferably of V-shaped cross-section, is provided with a series of vertical cylindrical chambers A, open at their lower ends and extending downwards through the cover C¹ nearly to the bottom of the molten lead or other liquid contact-substance E contained in the tank. Each cylinder is closed at the top 45 by a cover A¹, fitted with an oil or vapour-inlet pipe B, which extends downwards into the molten lead, and a vapour outlet pipe B¹ which connects with the inlet pipe of the adjacent chamber. Inspection plugs D are provided in the pipes B¹. The quantity of contact-substance in the tank, and the depths to which the cylinders A and inlet pipes B are respectively immersed in the lead, must be so adjusted as to ensure that the hydro- 50 carbon vapours flow in succession from cylinder to cylinder through the connecting pipes B¹, and pass out by the outlet pipe A², as indicated diagrammatically by the arrows, and do not escape beneath the lower edges of any 55 of the cylinders. A filling plug F for the mol-

ten lead is provided in the cover of the tank. To prevent oxidation of the lead, atmospheric air may be expelled from the tank by means of a reducing or indifferent gas or vapour: for example by introducing hydrocarbon oil 70 or vapour through the inlet C² and driving out the air through the outlet C³.

Figures 6 and 7 show, in sectional elevation and cross-section respectively, a modified arrangement in which the contact-substances 75 completely fills the covered tank C, and the vertical cylinders A, which are closed at their upper ends by the covers A¹, are connected by means of vapour pipes A², A³, and provided internally with vertical partitions A⁴ 80 which extend downwards for a short distance into the contact-substance. The cylinders A extend downwards nearly to the bottom of the contact-substance. The depths to which the cylinders A and partitions A⁴ are respectively immersed, in the lead must be so chosen 85 as to ensure that the hydrocarbon vapours flow through the apparatus as indicated diagrammatically by the arrows. The lower edges A⁵ of the partitions may be serrated 90 as shown in Figure 7. A chamber D, formed in the cover C¹ and communicating with the interior of the tank C, provides space for the expansion and contraction of the molten metal whilst minimizing the risk of oxidation 95 thereof. A plug D¹ gives access to the chamber for inspection or filling purposes.

It will be obvious that the apparatus shown in Figures 4 and 5 may be modified by substituting, for the form of tank therein shown, 100 a tank completely filled with the contact-substance as indicated in Figures 6 and 7.

The apparatus must in all cases be free from constrictions, interstices, or long channels of small cross-section, capable of being 105 obstructed by carbonaceous deposits, at parts where high temperatures are reached.

The inlet pipes are provided with feed-valves, preferably a non-return valve to prevent the escape of vapours, and a safety-valve or pressure gauge to guard against undue rise of pressure in case of accidental stoppage. The apparatus is also preferably provided with a pyrometer, the thermocouple of which is immersed in the contact-substance. The dephlegmators may be interposed between the chambers to facilitate the repeated treatment of the oil. It will be apparent that the dimensions of the apparatus may be varied according to the rate of 110 working desired, and that the number of oil or vapour inlet pipes may be increased in accordance with the capacity of the apparatus.

It has already been proposed to employ molten metal as a heating agent in the distillation of oils, oil residues, tar oils and other volatile substances—particularly those which when treated by the usual distillation methods leave a non-volatile residue. For example, it has been proposed to force the 115

oil or other volatile substances at constant rate and considerable velocity through a coiled pipe at least twenty feet long and of narrow bore (about three-sixteenths of an 5 inch diameter), heated externally by means of a bath of molten lead or other metal to a temperature sufficiently high to evaporate the constituent having the highest boiling point, a separating chamber, immersed in the 10 molten metal, being provided at the outlet of the coiled pipe for the separation of any unvaporized residue. In a proposed alternative form of apparatus the coiled pipe opened under the molten lead and at the bottom 15 thereof; the oil was thus heated during its passage through the coil and in rising through the molten metal it became further heated and vaporized without fractionation. The object and effect of this process were to 20 obtain continuously and uniformly either a distillate or vapour of constant composition, the volatile portion of the oil as it flowed through the apparatus being vaporized as a whole instead of being distilled over in fractions of progressively increasing density, as 25 in distillation by the usual methods.

The present invention, however, relates to the cracking of oils and not to the mere vaporization thereof and it is an essential feature 30 that the oil or vapours shall at no time be subjected to a cracking temperature in long or constricted pipes or other narrow channels, since the accumulation of carbonaceous deposits, which it is the object of the 35 invention to avoid, would inevitably occur therein. It is of the essence of the invention that the cracking shall take place solely in contact with the mobile metal itself, or substantially so, in order that the constant, vigorous 40 movement of the metal will prevent mechanically any local accumulations of deposit. I disclaim the use of molten metal in either the fractional or non-fractional vaporization of oils.

45 What I claim as my invention and desire to secure by Letters Patent is:—

1. Apparatus for cracking hydrocarbon oils and the like by means of a liquid contact substance, the apparatus comprising 50 an externally heated covered tank, said tank having a series of intercommunicating contact chambers therein, and means in each chamber for conducting the hydrocarbon below the level of the liquid contact substance 55 before its passage to the succeeding chamber, substantially as described.

2. Apparatus for cracking hydrocarbon oils and the like by means of a liquid contact substance, the apparatus comprising a 60 horizontal externally heated covered tank, said tank having a series of intercommunicating contact chambers therein, and means in each chamber for conducting the hydrocarbon below the level of the liquid contact substance 65 before its passage to the succeeding chamber, substantially as described.

ing chamber, all these elements being so disposed that the apparatus is free from constricted channels at points exposed to a cracking temperature, substantially as described.

3. Apparatus for cracking hydrocarbon oils and the like by means of a liquid contact substance, the apparatus comprising in combination a horizontally externally heated covered tank of V-shaped cross section 70 along an axis at right angles to its length, said tank having a series of intercommunicating contact chambers therein, and means in each chamber for conducting the hydrocarbon below the level of the liquid contact substance before its passage to the succeeding chamber, all these elements being so disposed that the apparatus is free from constricted channels at points exposed to a cracking temperature, substantially as described. 75

4. Apparatus for cracking hydrocarbon oils and the like by means of a liquid contact substance, the apparatus comprising an externally heated covered tank, said tank 90 having a series of intercommunicating contact chambers therein, and a depending partition in each chamber terminating below the level of the liquid contact substance for conducting the hydrocarbon below the level of 95 said substance before its passage to the succeeding chamber, substantially as described.

5. Apparatus for cracking hydrocarbon oil and the like by means of a liquid contact substance, the apparatus comprising an externally heated covered tank, said tank having a series of intercommunicating contact chambers therein, and a depending partition in each chamber terminating below the level 100 of the liquid contact substance for conducting the hydrocarbon below the level of said substance before its passage to the succeeding chamber, all these elements being so disposed that the apparatus is free from constricted channels at points exposed to a cracking temperature, substantially as described. 105

6. Apparatus for cracking hydrocarbon oils and the like by means of a liquid contact substance, the apparatus comprising in combination a horizontal externally heated covered tank, an expansion chamber for the contact substance in said tank, said tank having a series of intercommunicating contact chambers therein, and means in each 115 chamber for conducting the hydrocarbon below the level of the liquid contact substance before its passage to the succeeding chamber, substantially as described. 120

7. Apparatus for cracking hydrocarbon oils and the like by means of a liquid contact substance, the apparatus comprising in combination a horizontal externally heated covered tank, an expansion chamber for the contact substance in said tank, said tank 125 130

- 4
- having a series of intercommunicating contact chambers therein, and means in each chamber for conducting the hydrocarbon below the level of the liquid contact substance before its passage to the succeeding chamber, all these elements being so disposed that the apparatus is free from constricted channels at points exposed to a cracking temperature, substantially as described.
- 10 8. Apparatus for cracking hydrocarbon oils and the like by means of a liquid contact substance, the apparatus comprising in combination a horizontal externally heated covered tank, said tank having a series of intercommunicating contact chambers in the form of inverted pots, and means in each chamber for conducting the hydrocarbon below the level of the liquid contact substance
- 15

before its passage to the succeeding chamber, substantially as described.

9. Apparatus for cracking hydrocarbon oils and the like by means of a liquid contact substance, the apparatus comprising in combination a horizontal externally heated covered tank, said tank having a series of intercommunicating contact chambers in the form of inverted pots, and means in each chamber for conducting the hydrocarbon below the level of the liquid contact substance before its passage to the succeeding chamber, all these elements being so disposed that the apparatus is free from constricted channels at points exposed to a cracking temperature, substantially as described.

In testimony whereof I affix my signature. 35
JNO. NELSON.
